UNITED STATES PATENT OFFICE.

JOHN THEODORE FEAGER, OF ST. LOUIS, MISSOURI.

EGG-BASKET.

SPECIFICATION forming part of Letters Patent No. 404,349, dated May 28, 1889.

Application filed March 31, 1888. Serial No. 269,080. (Model.)

To all whom it may concern:

Be it known that I, JOHN THEODORE FEAGER, of St. Louis, Missouri, have made a new and useful Improvement in Egg-Baskets, of 5 which the following is a full, clear, and exact description.

This device is designed more especially for farmers' uses—that is, a case filled with eggs can be placed within the basket, then carried 10 in a wagon to town, and then unloaded and returned, and in removing the contents of the package not only the eggs, but also the case, as stated, can be taken out of the basket, leaving the basket to be otherwise used upon 15 the return-trip, and to receive another case when used another time, all substantially as shown in the annexed drawings, making part of this specification, in which—

Figure 1 is a view in perspective of the 20 improvement, the basket-cover being raised; Fig. 2, a vertical cross-section of the same, the cover in place and the handle upturned; Fig. 3, a view in perspective of the case, and Fig. 4 a vertical longitudinal section of one 25 end of the improved basket.

The same letters of reference denote the same parts.

A represents the basket proper, and A' the 30 cover, both made of wicker-work, and B represents the case. As illustrated in the drawings, the basket has two handles, a a, and they are so made and applied to the body a' of the basket as to enable them to be turned upward over the basket-body a' and top a² 35 and to be turned downward to come snugly against the lower corners, a³ a³, respectively, of the basket, and thus to present no obstacle to the packing of the basket with other articles in the bed of a wagon or other place. This 40 position of the handles is shown in Fig. 1. The basket-top a² can be fastened to the basket-body a' by means of the catch a⁴.

The case B, which is made in any of the 45 usual and ordinary ways, and may be rigid or adapted to fold, as may be desired, by means of suitable partitions, b b', is divided into the usual compartments, b², in which the eggs to be carried are placed. The case and basket are so relatively constructed as to provide 50 a space, C, between the bottom b³ of the case and the bottom a⁵ of the basket. A similar space, C', is formed at each side between the case side b⁴ and the basket-side a⁶, as

shown in Fig. 2. A similar space, C², Fig. 4, is formed between the case end b⁵ and the 55 basket end a⁷. By applying the top a², as shown in Figs. 2 and 4, a space, C³, is formed above the case beneath the basket-top. The case at its edges b⁶, projecting below the bottom, comes in contact with the basket, and 60 also at or toward its upper portion, b⁷, substantially as shown in Figs. 2 and 4.

The upper portion, a⁷, of the part A of the basket is made by a rectangular hoop of smaller dimensions than the body of the basket, around which the wicker-work is woven. Consequently this edge is slightly contracted, as shown in Fig. 2, to afford a binding action upon the egg-case, so as to hold it tight and firm in position when placed within it, and 70 there is also thereby provided the shoulder a⁸ on the outside for the cover to rest upon. In this manner a very safe, convenient package is provided for the purpose in view. During the transportation of the package the 75 wicker-work construction of the outer portion of the package of itself is an efficient means for guarding the inner portion of the package, irrespective of the spacing apart, as described, of the two portions of the package. 80 Such spacing apart, however, is of material value in promoting the safety of the contents of the case, and it also may, when vacant, be useful for ventilation purposes.

If desired, an elastic or equivalent packing 85 may be used between the portions A B of the package.

I claim—

1. The within-described device, consisting of the wicker-work basket A, having an upper portion, a⁷, and a shoulder, a⁸, combined with the egg-case B, having plain walls, as and for the purpose stated.

2. The wicker-work basket A, having the upper binding portion, a⁷, combined with 95 the egg-case B, having plain walls projecting below its bottom, whereby the case comes in contact with the basket at its bottom edges, b⁶, and at its upper portion, b⁷, and a ventilating-space is provided between the sides and 100 bottoms of the case and basket, substantially as set forth.

J. THEODORE FEAGER.
